UNITED STATES PATENT OFFICE.

HERBERT CLAYTON, OF CINCINNATI, OHIO.

SIFTER.

SPECIFICATION forming part of Letters Patent No. 291,576, dated January 8, 1884.

Application filed March 22, 1883. (No model.)

To all whom it may concern:

Be it known that I, HERBERT CLAYTON, of Cincinnati, in the county of Hamilton and State of Ohio, have invented certain new and useful Improvements in Sifters; and I do hereby declare the following to be a full, clear, and exact description of the invention, such as will enable others skilled in the art to which it pertains to make and use it, reference being had to the accompanying drawings, which form part of this specification.

My invention relates to improvements in sifters; and it consists in the combination of the sifter-frame, which has its two ends pivoted together at their upper edges, and which are adapted to open outward at their lower edges, a latch for holding the frame closed, a removable sieve, crank-shaft, and the revolving frame, which forces the substances being sifted through the sieve, and a pin for locking the revolving frame to the shaft, as will be more fully described hereinafter.

The object of my invention is to provide a sifter in which the sieve is made readily removable, either for the purpose of cleaning it or for the purpose of replacing it by another, and in which the revolving frame can be readily detached from the crank-shaft for the purpose of enabling it to be cleaned.

Figure 1 is a side elevation of the sifter-frame, showing it open for the removal of the sieve. Fig. 2 is a vertical cross-section. Fig. 3 is a detail view of the revolving frame.

A represents the sifter-frame, which is preferably made of a tubular shape, and provided with a handle, B, in the usual manner. The ends of this frame A are pivoted together at O, while the lower edges of these ends have no other means of connection than the wire C, which projects from one side and passes into a suitable socket, b, which is formed upon the opposite one. By connecting these ends together at their upper edges and allowing the lower edges to be drawn apart, the frame can be opened, as shown in Fig. 1, for the purpose of allowing the sieve F to be readily removed. The wire C is fastened in the lower edge of the frame A, for the pur-

pose of strengthening it, and one end is allowed to project, as shown, for the purpose 50 of forming a guide and bringing the edges together.

In the frame, at any suitable point, there is formed a groove, H, in which the upper edge of the sieve F is made to catch. As 55 long as the frame is closed, as shown in Fig. 2, this sieve will be held securely in place; but when the lower portion of the frame A is open, as shown in Fig. 1, the sieve can be readily removed. For the purpose of holding 60 the two ends of the frame tightly together, the notched latch G is provided. By thus making the sieve removable, sieves of different grades can be used in the same frame, and the sieves can be removed and replaced with 65 but little trouble when it is desired to clean them.

The revolving frame J, which is secured to the crank-shaft L, is locked to the shaft by means of the pin or wire I, which passes 70 down through one of the ends of the revolving frame J and through the crank-shaft. After the sieve has been used and it is desired to remove the frame and the crank-shaft for the purpose of washing them thoroughly, it is 75 only necessary to pull out the pin, and then the crank-shaft can be drawn out and the revolving frame removed.

Pin I is made from a single piece of wire, which is bent near its center into one or more 80 coils, so as to form a spring, and which has a hook formed on one of its ends. This pin forms a locking device which cannot become accidentally displaced as the frame is being revolved.

It will readily be seen that the crank-shaft L extends through one end of the frame J, and thus it is only necessary to provide the frame with a pivot, d, upon the opposite side or end. By this construction the long rod 90 which usually passes through the center of the frame is entirely dispensed with.

Having thus described my invention, I claim—

1. A sifter-frame which has its ends pivoted together near their upper edges, and which

is provided with the guiding-wire C and the socket b at its lower edges, and a pivoted locking-latch, G, in combination with the sieve F and revolving frame J, substantially as shown.

2. A revolving frame, J, provided with the pivot d, the short crank L, and a spring locking-pin, I, in combination with the frame

A and sieve F, substantially as shown and described.

In testimony whereof I affix my signature in presence of two witnesses.

HERBERT CLAYTON.
